UNITED STATES PATENT OFFICE.

NELS HALVERSON, OF STOUGHTON, WISCONSIN.

VEHICLE-SPRING.

SPECIFICATION forming part of Letters Patent No. 759,368, dated May 10, 1904.

Application filed August 18, 1903. Serial No. 169,941. (No model.)

To all whom it may concern:

Be it known that I, NELS HALVERSON, a citizen of the United States, residing at Stoughton, in the county of Dane and State of Wisconsin, have invented new and useful Improvements in Vehicle-Springs, of which the following is a specification.

This invention relates to vehicle-springs.

The object of the invention is the provision of a durable and efficient vehicle-spring which can be easily adjusted for light or heavy loads, will prevent bounding of the springs, and compensate for jars and strains of all kinds.

Further objects are to provide a novel arrangement of the springs to economize in material and eliminate "dead-spring" areas and to hang the springs in an improved manner.

The invention is set forth in detail herein-after, and the novel features and combinations of parts thereof are embodied in the appended claims.

In the accompanying drawings, Figure 1 is a side elevation; Fig. 2, a perspective view of one-half of the device; Fig. 3, detached details of the hangers for the inner ends of the main springs; Figs. 4 and 5, details of modified forms of hangers which are coupled together; Fig. 6, a section on line $\alpha-\alpha$ of Fig. 5; Fig. 7, enlarged details of a modified form of hanger, and Fig. 8 detached details of the hangers of Fig. 7.

The vehicle-bed 1 is supported on the bolster 2. At the ends of the bolster are guide-clips 4 for the free ends of the leaf of the upper section of the springs 5 and 6 to slide therein.

The springs 5 and 6 are each composed of upper and lower sections or leaves 7 and 8, the inner ends of which are embraced by a clip 9, having struck-up ridges 10 in its legs and receiving similar struck-up portions 11, formed on the leaves of the springs.

A U-shaped shackle 12 embraces the clip and spring and has its yoke received in the struck-up ridge 10 on the lower leg of the clip. A clamp-plate 13, conformed to the ridge 10 of the upper leg of the clip 9, is provided at or near its middle with opposite notches 14. The legs of the shackle 12 pass through openings 15 in the ends of the clamp-

plate 13, and nuts 16 on said legs clamp the parts firmly together.

A U-shaped hanger 17, secured to the bolster 2, has its yoke passed under the clamp-plate 13 transversely thereof and is received in the notches 14. This hanger construction while permitting longitudinal movement of the springs prevents lateral movement thereof.

Beneath the lower leaves 8 of the main springs 5 and 6 is a single supplemental or compensating spring 18.

The springs 7 and 18 are connected to removable bolts 19 and 20, forming parts of shackles 22. The bolts 19 have crank portions 23, journaled in bearings 24 on the axle 25.

Depending from the bolster 2 are limit-bars 26, having rubber-covered ends 27, on which bolts 19 rest. These limit-bars prevent bounding of the springs upwardly.

In the foregoing construction the supplemental spring 18 compensates for tilting of the main springs 5 and 6 and equalizes the strains and jars to which they are simultaneously or independently subjected. The hangers permit the main springs to move longitudinally, and the guide-clips also permit this movement. The hanger and clip and shackle construction permits easy removal or addition of the spring-leaves, so that the springs can be tensioned to suit any load from the lightest to the heaviest. The provision of independent main springs eliminates the use of dead-spring area and renders repair cheaper and easier than with the ordinary single spring in common use.

In the modification shown in Figs. 4, 5, and 6 the clips 28 and spring-leaves have struck-up nested portions 29, made by the use of a center punch, and upper and lower clamp-plates 30 are formed in the same piece with said clips and connected by bolts 31. Secured on the upper clamp-plates by the bolts 31 are yokes 32, which are coupled together by links 33, and the yokes 32 are hung in bearings 34 on a plate 35, secured to the bolster. This construction causes the main springs 5 and 6 to move together longitudinally thereof.

In the modification of Fig. 8 the clip is similar to clip 28, except that struck-up ridges 36 are formed in the spring and clip. The yoke 100

37 is rounded and hung from a rounded hanger 38, secured to the bolster. This construction permits the springs to move both laterally and longitudinally. The hangers are not connected.

5 In the various forms the supplemental spring strengthens the entire device and is made removable at will by taking out the bolts 20.

10 Having thus described my invention, what I claim as new, and desire to secure by Letters Patent, is—

15 1. The combination with a bolster, of two hangers near the middle thereof, two separate main springs each composed of upper and lower sets of leaves diverging from a common point of pivotal connection with one of said hangers, the upper sets bearing at their outer ends against said bolster, a supplemental 20 spring extending lengthwise of the bolster, and shackles connecting each end of said supplemental spring with the outer end of the lower set of leaves in the adjacent main spring.

25 2. In a vehicle-spring, the combination of separate main springs each consisting of diverging leaves, of separate hangers connected to the respective springs at their point of

convergence, said hangers pivotally suspending the main springs, and a coupling connecting said hangers to cause the springs to move together.

3. In a vehicle-spring, the combination with a plurality of leaves having registering struck-up portions near one end, of a U-shaped clip receiving said ends and having similar struck-up portions, and provided with laterally-projecting ears, and clamping - bolts passing through said ears outside of said leaves.

4. The combination with a bolster, of leaf-springs suspended therefrom, and stationary 40 limit-bars engaging the outer ends of said springs to limit the play thereof.

5. The combination with a bolster, of leaf-springs suspended therefrom near its middle, and hooked limit-bars secured to the ends of 45 said bolster and engaging the outer ends of said springs.

In testimony whereof I have signed my name to this specification in the presence of two subscribing witnesses.

NELS HALVERSON.
